DOOR CONSTRUCTION

Vernon H. Springford and William Herbert Ellis,
Evansville, Ind., assignors to Servel, Inc., New
York, N. Y., a corporation of Delaware

Application January 23, 1933, Serial No. 653,122

13 Claims. (Cl. 20—35)

This invention relates to cabinet door construction and more particularly to door construction employed in the manufacture of refrigerators.

Doors of this character ordinarily are formed of two sheet metal shells having insulation therebetween and with or without a frame connecting these shells at their edges and with a suitable trim or finish for the contiguous edges of the shells.

10 It is an object of the present invention to provide a finish or trim for the edge of the door, which trim is of improved appearance, of reduced cost, of durable construction, and which will minimize heat leakage.

15 A further object of the invention is to provide a construction requiring a minimum of labor in assembling or disassembling and in which all fastening elements are concealed.

20 Other objects and advantages will be apparent from the following description taken in connection with the accompanying drawing, wherein,

Fig. 1 is a horizontal section of a door constructed in accordance with the present invention and showing a cabinet in dotted lines;

25 Fig. 2, a slightly enlarged fragmentary detail of a slightly modified construction; and

Fig. 3, a horizontal fragmentary detail of a further slightly modified door construction.

Referring to the drawing, the door is formed of inner and outer metal plates 10 and 11 respectively having insulation 12 being confined between them and with an annular frame consisting of inner and outer sections 13 and 14 respectively. The outer shell or plate 11 has its edge curled around a thin flange 14' of the outer frame member 14 against the inner surface of which flange 14' a gasket 15 is adapted to be compressed and held in place by the frame section 13 and a finishing strip 16.

40 The frame sections 13 and 14 are cut to form right angular complementary surfaces, and the outer surface of the frame member 13 is inclined or beveled at an angle substantially corresponding to the inclination of the beveled door frame 45 of a cabinet, as shown. To this inclined or beveled surface a finish may be applied in the form of a separate strip 16 having a pyralin coating 17 as shown in Figs. 1 and 2; or the pyralin finish may be applied directly to the frame member, as shown in Fig. 3. The strip 16 is fastened in place by concealed fastening means such as nails 18.

45 In the construction of a door such as that shown in Fig. 1 the door pan 11 is first formed 50 of four frame members 14 which are applied one

at each side of the door to form an annular frame section and the inner frame member 13 has the trim strip 16 applied thereto, whereupon the inner frame section 13 is applied upon the outer frame section 14 and is fastened thereto by means of screws or other fastening elements 5. The gasket 15 has its inner edge or bead 15' clamped in a groove 13' in the lower outer edge of the frame member 13.

10 In Fig. 2 the parts are identical except an inner frame member 13a of slightly modified construction is provided, said member 13a having a groove 13a' spaced slightly inwardly from the outer edge as is also the case in Fig. 3.

15 The inner door plate or pan 10 is applied lastly and is secured in place by fastening elements 20. It will be understood, of course, that the finish 16 for the door is, like the frame, of non-heat-conducting material and the coating 17 therefor is of durable, resistant, heat insulating 20 material as for example, pyralin, or the like, and it may be applied in sheet form or sprayed directly upon its base.

25 It will be obvious to those skilled in the art that various other changes may be made in the construction and arrangement without departing from the spirit of the invention and therefore the invention is not limited to what is shown in the drawing and described in the specification but only as indicated in the appended claims.

30 What is claimed as new is:

1. Cabinet door construction comprising cooperating frame sections forming when assembled an annular frame, an outer plate carried by one of said frame sections, an inner plate carried by another frame section, and a gasket clamped by and between said frame sections and extending along the edge of the door.

2. A refrigerator door comprising inner and outer frame members, inner and outer plates carried by said frame members, a gasket clamped by and between said frame members, one of the frame members being provided with a beveled finishing surface and a protective sheath for said surface and giving it the appearance of a breaker 45 strip.

3. A refrigerator door comprising a door frame, inner and outer plates secured to the door frame, means for binding said plates together transversely of the door frame, and a non-hygroscopic 50 thin protective finishing member for the periphery of said frame.

4. A refrigerator door comprising a door frame, inner and outer plates secured to the door frame, means for binding said plates together trans- 55

versely of the door, a gasket clamped by and between portions of the door frame, a thin protective finishing member for the periphery of said frame and concealed means for fastening said protective finishing member in position.

5. A refrigerator door comprising inner and outer metal plates, an independently formed marginal frame for each of said metal plates, said marginal frames being complementarily formed to overlap substantially parallel to and substantially transversely of said plates, the outer surface of one of said frames being transversely beveled, said bevel being inclined inwardly from the outer plate toward the inner plate to 10 provide a surface substantially parallel to the receiving opening of a cabinet adapted to be closed by said door.

6. A refrigerator door comprising inner and outer metal plates, an independently formed 20 marginal frame for each of said metal plates, said marginal frame being complementarily formed to overlap substantially parallel to and substantially transversely of said plates, the outer of said frames being transversely beveled, said 25 bevel being inclined inwardly from the outer plate toward the inner plate to provide a surface substantially parallel to the receiving opening of a cabinet adapted to be closed by said door, and a protective sheath for said beveled surface.

30 7. A refrigerator door comprising inner and outer metal plates, an independently formed marginal frame for each of said metal plates, said marginal frames being complementarily formed to overlap substantially parallel to and substantially transversely of said plates, the outer surface of one of said frames being transversely beveled, said bevel being inclined inwardly from the outer plate toward the inner plate to provide a surface substantially parallel to the receiving opening of a cabinet adapted to be closed by said door, and a protective sheath for said beveled surface, and concealed fastening means for securing said sheath in position.

35 8. A refrigerator door comprising inner and outer metal plates, an independently formed marginal frame for each of said metal plates, said marginal frames being complementarily formed to overlap substantially parallel to and substantially transversely of said plates, the outer surface of one of said frames being transversely beveled, said bevel being inclined inwardly from the outer plate toward the inner plate to provide a surface substantially parallel to the receiving opening of a cabinet adapted to 40 be closed by said door, a protective sheath for said beveled surface, concealed fastening means for securing said sheath in position, and a gasket clamped in position by said sheath.

45 9. A refrigerator door comprising inner and outer metal plates, a marginal frame for each

of said metal plates, said marginal frames being complementarily formed to overlap substantially parallel to and substantially transversely of said plates, the outer surface of one of said frames being transversely beveled, said bevel being inclined inwardly from the outer plate toward the inner plate to provide a surface substantially parallel to the receiving opening of a cabinet adapted to be closed by said door, and a protective sheath for said beveled surface, said sheath being applied directly to said beveled surface.

5 10. A refrigerator door comprising inner and outer complementary frame sections secured together, each of said frame sections having a peripheral flange, the flange on the inner section extending substantially to the outer surface of the door and being beveled to correspond to the inclination of the door frame of the refrigerator, and a gasket clamped between said peripheral flanges of the frame sections.

15 11. A refrigerator door comprising complementarily formed inner and outer annular substantially L-shaped frame sections having portions overlapping transversely and longitudinally of the door, a gasket clamped between the portion of one frame section disposed longitudinally of the door and another frame section located transversely of the door, the transverse portion of one of the frame sections forming the periphery of the door, and a relatively thin finishing sheath for said periphery.

20 12. A door designed to prevent heat transfer comprising an annular frame formed of complementary sections having portions overlapping transversely and longitudinally of the door, said annular frame having a marginal flange formed by an extension of one of said sections, a gasket disposed in a manner to be compressed by said flange when the door is closed, said gasket being clamped between the flange of the frame section and one of the other frame sections and thereby held in place.

25 13. A door designed to prevent heat transfer comprising an annular frame formed of complementary sections having portions overlapping transversely and longitudinally of the door, said annular frame having a marginal flange formed by an extension of one of said sections, a gasket disposed in a manner to be compressed by said flange when the door is closed, said gasket being clamped between the flange of the frame section and one of the other frame sections and thereby held in place, concealed means for removably fastening said frame sections together, a transverse periphery of the frame forming a periphery of the door, and a relatively thin finishing sheath for said periphery.
